UNITED STATES PATENT OFFICE

141,291

DESIGN FOR A TRUCK

John J. Powers, St. Louis, Mo.

Application February 28, 1945, Serial No. 118,170

Term of patent 14 years

(Cl. D14—3)

To all whom it may concern:

Be it known that I, John J. Powers, a citizen of the United States, residing at the city of St. Louis, State of Missouri, have invented a new, original, and ornamental Design for a Truck, of which the following is a specification, reference being made to the accompanying drawing, forming a part thereof, in which Figures 1 and 2 are perspective views from the right and left-hand sides, respectively, and Figure 3 is a rear perspective view of a truck embodying my new design.

I claim:

The ornamental design for a truck, substantially as shown.

JOHN J. POWERS.
